THOMAS POWELL, OF MILROY, INDIANA.

Letters Patent No. 63,092, dated March 19, 1867.

IMPROVEMENT IN SLEEVE SUPPORTERS.

The Schedule referred to in these Letters Patent and making part of the same.

TO ALL WHOM IT MAY CONCERN:

Be it known that I, THOMAS POWELL, of Milroy, in the county of Rush, and State of Indiana, have invented a new and improved Supporter for Shirt Sleeves; and I do hereby declare that the following is a full, clear, and exact description thereof, which will enable others skilled in the art to make and use the same, reference being had to the accompanying drawings, forming part of this specification.

The present invention relates to a new and improved supporter, more especially designed for the sleeves of shirts, although it can be used to advantage upon the sleeves of other articles of wearing apparel; the object being to produce a supporter for such use which will be comfortable and easy to the wearer.

In the accompanying plate of drawings my improved shirt-sleeve supporter is illustrated, the figure being a view of the supporter as applied or worn upon the arm.

A, in the drawings, represents the supporter, which consists of a band, B, made of India rubber or any other suitable elastic material or materials, having at one end a ring or loop, C, and at its other a hook, D, the former being secured by stitching or sewing, and the latter by means of a buckle, E, or any other fastening, which will allow the hook to be adjusted in its position upon the band B.

When the supporter A is worn it is looped around the arm above the elbow, by passing the end of the band B, having the hook through the ring or loop C, as plainly shown in the drawing, when, fastening the hook to the end of the slit in the shirt sleeve, the necessary support is given to the sleeve upon the arm, and in such a manner as to produce or occasion no uneasy or uncomfortable feeling to the arm of the wearer. In lieu of the hook D a button may be used.

I claim as new, and desire to secure by Letters Patent—

The elastic band B, provided at one end with the ring C, through which it passes after encircling the arm above the elbow, and having at its lower end the hook D, adapted to catch it in the slit of the sleeve, as herein described and represented.

THOMAS POWELL.
